UNITED STATES PATENT OFFICE.

DAVID F. DOMIZI, OF FRANKLIN, PENNSYLVANIA.

MACHINE FOR GRINDING THE LATERAL FACES OF PISTON-RINGS.

1,139,649.

Specification of Letters Patent. Patented May 18, 1915.

Application filed January 20, 1912. Serial No. 672,503.

To all whom it may concern:

Be it known that I, DAVID F. DOMIZI, citizen of the United States, residing at Franklin, in the county of Venango and State of Pennsylvania, have invented certain new and useful Improvements in Machines for Grinding the Lateral Faces of Piston-Rings, of which the following is a specification.

The object, application, construction and operation of my improved grinding machine for the lateral faces of piston rings are herein set forth with sufficient clearness to enable those skilled in the art to which it appertains, to make and use the same.

In the manufacture of snap rings for the pistons of high speed motors, such as are used in automobiles, motor boats, etc., it is necessary that the rings be accurately finished, and especially that the width of the ring be such as to accurately and nicely fit the groove made to receive the same in the piston. In order to properly accomplish this finishing, it is necessary that it be done by grinding, and it is for this purpose that I have invented the machine here shown.

Briefly stated, my improved grinding machine consists of two abrasive wheels, adjustably mounted side by side upon a single mandrel and having their juxtaposed, lateral faces arranged to simultaneously grind the two lateral faces or edges of the piston ring, or any similar article, said mandrel being revolvably mounted in any suitable frame or bed adapted to be attached to a suitable machine tool provided with a chuck for receiving and revolving the ring as the edges are being ground by said abrasive wheels.

In the form in which I have here shown my machine, it is designed and adapted to be applied to a lathe, but this is merely one of several possible adaptations of the same, as it may be applied to other standard types of machine tools, as well as to a specially constructed machine for this purpose alone.

One form of construction of my improved grinding machine, is clearly set forth in the drawings, which form a portion of this specification, the various figures of which are as follows:

Figure 1 is a plan view of said machine; Fig. 2 is a central, longitudinal section of the mandrel and the attached wheels; this view being included more for the purpose of showing merely essential elements, rather

than actual construction; Fig. 2^A is a modified form of mandrel and the one which I prefer to usually employ, though it differs but little from Fig. 2; Fig. 3 is a transverse section upon line III III of Fig. 2^A; Fig. 4 is a transverse section upon line IV IV of Fig. 2^A; Fig. 5 is a side elevation of my machine, showing the same attached to a lathe, the lathe bed and apron being shown in section.

The construction shown in the drawings is substantially as follows: Two abrasive wheels, 1 and 2, are mounted side by side upon a single mandrel, which is composed of a non-revolute shaft 3 and a compound revolute sleeve, consisting of the member 4, to which wheel 1 is attached, and member 5 to which wheel 2 is attached; sleeve 5 is longitudinally adjustable upon sleeve 4, and said sleeves are caused to revolve in unison by means of the spline 6. Said longitudinal adjustability of sleeve 5 and its attached wheel 2, is for the purpose of providing a lateral adjustment of said wheel, and for varying the width of the space or gap 7 between the wheels 1 and 2, and by which the desired width of the piston ring is secured. Means for accomplishing this adjustment consists of the externally-threaded sleeve 8, which passes through an internally-threaded nut 9, that is revolvably mounted in the bearing 10. A hand-wheel 11 is affixed to said nut, for the purpose of revolving same when an adjustment is to be made. A chamber 12 is formed in the sleeve for the reception of a spring 13, which bears at one end upon sleeve 4 and at the other end upon a portion of sleeve 5, and prevents any unintended, relative, longitudinal movement thereof. Said spring also moves wheel 2 and sleeve 5 toward sleeve 8, when said sleeve 8 is retracted in making adjustments. Said spring also serves to automatically maintain the adjustment of said wheels and sleeves, as against any wear in the thread of sleeve 8 or the thrust-bearing 14, which might otherwise and without said spring tend to cause inaccuracies by a possible relative lateral play of the wheels 1 and 2. Any suitable dust-proof joint, as a telescopic joint 15, may be provided upon the sleeves 4 and 5, between the wheels, for the purpose of excluding abrasive material from the wearing surface of the sleeves and shaft 3.

The bearings 10 and 16 are an integral portion of the bed or frame 17, in which the

wheels 1 and 2 and the mandrel are mounted; a pulley 18 is attached to sleeve 5, for the reception of a driving belt, whereby the wheels are driven.

5 In Fig. 2^A, I have shown a modified form of mandrel, which is essentially the same as Fig. 2, except that I have provided a somewhat more minute adjusting means than I have shown in Fig. 2. I have also 10 provided a different arrangement of spring 13, which is designated 13' in Fig. 2^A. Specifically set forth, the construction shown in Fig. 2^A is as follows: 1 and 2 are the abrasive or grinding wheels, 3 is the non-revolv- 15 able shaft, 4 and 5 are the respective sleeves of the compound mandrel. The office of the key or spline 6 is performed by the rods 6', which rods also have another office to be presently set forth; 8' is an adjusting 20 sleeve, which is longitudinally movable, said movement being accomplished in one direction, by means of the worm-wheel nut 9', and in the other, by the reaction or expansion of spring 13'; a worm 11', which en- 25 gages wheel 9', is employed for revolving said wheel. Sleeve 8' bears against the contiguous end of sleeve 5 through the medium of the anti-friction washers 14'. A housing or case 19 is non-revolubly fixed in the bearing 10, in which worm 11' is mounted, and said housing is extended in the direction of the wheels, in the form of the sleeve, for the purpose of excluding fine particles of abrasive material from the thrust-bearing 14'. 30 The application of spring 13' differs from the application of spring 13 of Fig. 2, in the following particulars: Said spring is located upon the outside of sleeve 5, and bears at the inner end against the annulus 35 20, which annulus, in turn, bears against the outer end of rods 6', that pass loosely through the wheel-flange 21 of sleeve 5. The inner ends of rods 6' are firmly se- 40 cured in the other wheel-flange 22. The 45 outer end of spring 13' bears against a col- ller 23, which is connected by means of a screw-thread to sleeve 5. The reaction or expansive tendency of springs 13' causes sleeve 5 to bear forcibly against the adjust- 50 ing sleeve 8', through the medium of the thrust-bearing 14, as aforesaid. The tension or expansive force of the spring, and the consequent pressure of sleeve 5 against sleeve 8, may be regulated by the position of col- 55 ller 23. This action of said spring also causes a separating tendency between the wheels 1 and 2, and thereby accomplishes the same automatic take-up of wear that is secured by means of the spring in Fig. 2. 60 A suitable hand-wheel 11'' is provided for the manipulation of worm 11'. Graduations are formed upon said wheel 11'', and an index 11^a is attached to sleeve 19, and is pro- 65 vided with a point which is positioned in close proximity to said graduations, to in-

dicate the passage and location of same, and the degree of adjustment being made.

A suitable anti-friction or thrust-bearing 14^a is provided for sleeve 4, which, in Fig. 2^A, is shown as a plurality of washers, and, 70 by altering the thickness or number of said washers, a certain amount of longitudinal adjustment of said sleeve 4 or lateral adjustment of wheel 1 is provided for.

In Fig. 5, I have shown my machine attached to the slide-rest 24 of a lathe, and from an inspection of this view, it will be apparent that the grinding-wheels are adapted to be moved to and away from their work by means of the cross-feed 25, the same 75 as an ordinary lathe-tool. The ring 20 is shown in dotted lines in Fig. 5, and for the purpose of holding the ring while being finished, I prefer to use the chuck shown and described by me in a certain applica- 80 tion for Letters-Patent of the United States, filed April 21, 1911, Serial No. 622,579.

I have shown frame 17 extended and adapted for the attachment of a certain gage-tool 27, which is fully described in a 90 certain application for Letters Patent filed by me on the 20th day of January, 1912, Serial No. 672,502.

As is well known, the saddle 28 of all lathes is movable longitudinally of the bed, 95 and the slide or tool-rest 24, to which my device is attached, is movable upon the saddle transversely of the bed, and because of this, every adjustment which could possibly be utilized, is provided in the construction 100 here shown. The transverse movement of the slide 24, accomplished by means of the handle 25, is the one whereby the feed of my device is accomplished, or, in other words, this is the provision whereby wheels 1 and 105 2 are moved into the operative position and into contact with the work to be done, and removed therefrom.

I attach my device to the rest 24 in any convenient way or suitable means, the means 110 here shown being a bolt 29, the head of which is inserted into the tool-post slot 30 and passed through an eye 31 upon the carriage or frame 17.

I claim—

1. In a machine for grinding the lateral edges of piston rings, the combination of two abrasive wheels adjustably mounted upon one mandrel, and arranged for simultaneously grinding the lateral edges of a 120 piston ring, a frame for said wheels arranged to be movable in a line transverse to the axis of said wheels, and means for revolving such ring during the grinding operation.

2. In a machine for grinding the lateral edges of piston rings, the combination of two abrasive wheels adjustably mounted side by side upon one mandrel, with their contiguous faces arranged to simultaneously grind the 130

lateral faces of such ring, and means for varying the distance between said contiguous faces, a frame in which said wheels are mounted, movable in a line transverse to the axis of said wheels, and means revolving such ring during the grinding operation.

5. In a machine for grinding the lateral faces of piston rings, the combination with two abrasive wheels contiguously mounted upon a mandrel, and relatively adjustable thereon, of a frame arranged for the operative reception of said mandrel and wheels, and for their attachment to a suitable machine tool, having a work-spindle or live center whereby said wheels are adapted to operate upon a ring, when revolved by said spindle.

10. In a machine for grinding the lateral faces of piston rings, the combination with the slide-rest, of a lathe, which lathe is equipped with means for holding and revolving such ring during the grinding operation, of a frame attached to said rest,

25 and movable therewith, a mandrel revolvably mounted in said frame, abrasive wheels contiguously and adjustably mounted upon said mandrel, means for varying the contiguity of said wheels, and means for driving said wheels.

30. In a machine for grinding the lateral faces of piston rings, the combination of two abrasive wheels, contiguously, adjustably mounted upon a mandrel, and arranged to simultaneously grind the lateral faces of such ring, means for varying the degree of 35 said contiguity, means indicating the amount of said variation and means automatically preventing possible relative, lateral play between wheels, which might be caused by wear of operative parts.

40 In testimony whereof I affix my signature in presence of two witnesses.

DAVID F. DOMIZI.
